COMBINED VENTILATOR AND SKYLIGHT

Thomas R. Field, Indianapolis, Ind., assignor to Jenn Air Products Company, Inc., Indianapolis, Ind., a corporation

Filed Dec. 28, 1959, Ser. No. 58,830

Term of patent 14 years

(Cl. D62—3)

Fig. 1 is a front perspective view of a combined ventilator and skylight showing my new design;

Fig. 2 is a front perspective view of a modified form thereof; and

Fig. 3 is a front perspective view of a further modified form thereof.

The dominant features of my design reside in the portions shown in full lines. The right side is substantially the same as the left side shown and the rear is a mirror image of the front shown.

I claim:

The ornamental design for a combined ventilator and skylight, as shown and described.
